UNITED STATES PATENT OFFICE.

JOHN A. FRASER, OF NILES, MICHIGAN, ASSIGNOR TO KAWNEER MANUFACTURING COMPANY, OF NILES, MICHIGAN, A CORPORATION OF MICHIGAN.

METAL-FORMING MACHINE.

1,227,604.

Specification of Letters Patent. Patented May 29, 1917.

Application filed January 21, 1914. Serial No. 813,600.

To all whom it may concern:

Be it known that I, JOHN A. FRASER, a citizen of the United States, residing at Niles, in the county of Berrien and State of Michigan, have invented new and useful Improvements in Metal-Forming Machines, of which the following is a specification.

This invention relates to a machine for forming blank strips of metal stock into commercially useful forms.

More specifically the illustrative embodiment of the invention herein disclosed relates to a machine for forming blank strips of metal stock into commercially useful forms by the operation thereupon of a plurality of sets of forming rolls, the rolls varying in their operating contour progressively through the machine, whereby the stock is gradually formed from a flat strip into the form desired.

It is an object of my invention to provide compact convenient easily running driving gear for a machine of the character described.

Another object of my invention is to provide means whereby it is possible to interchange and substitute rolls of varying sizes and widths in order to produce forms of different shapes in the same machine.

Another object of this invention is to make a comparatively inexpensive, thoroughly efficient and practical machine of the character described.

Another object of my invention is to provide a single driving shaft whereby all the forming rolls used in the machine are positively driven, this result being accomplished in the preferred form of the invention herein disclosed by means of worms and worm gears upon the driving shaft and the roll shafts respectively.

Another object of my invention is to actuate all of the rolls by parallel shafts positively connected therewith, the connection however being detachable whereby the rolls may readily be removed from the shafts and replaced by other rolls.

Another object of my invention is to provide flexible shafts positively connected with

one set of the forming rolls in such a fashion as to permit ready adjustment of the axes of these rolls toward or away from the axes of the other set without disturbing the operation of the machine.

A further object of my invention is to provide adjustable bearing standards for the rolls made up of a plurality of interlocking parts connected by comparatively few bolts and to provide ready means for the adjustment of said standards either bodily one part toward the other, or as concerns portions thereof in which the roll axes are mounted whereby I obtain a strong and durable structure, yet, one possessing a high capacity for easy adjustment and capable at the same time of being quickly knocked down or disassembled for the repair, replacement, etc., of any of its parts.

Another object of my invention is to provide certain new easily adjusted straightening devices for the finished product of the machine.

Other objects and advantages of my invention will appear as the description to follow proceeds.

In the specified form herein disclosed, the invention is illustrated in connection with a machine particularly designed to make tubes from blank sheet metal stock by successive operations of a plurality of rollers each of which forms the stock into a certain definite form.

The invention, however, also includes within its scope, the application of other rollers in a place of the particular set here designed for the purpose of creating tubes having longitudinal recesses therein such as are commonly used for plate glass settings or any other form capable of being turned out by the successive operation of a plurality of forming rollers.

In the drawings

Figure 1 is an end elevation showing the ingress end of my machine.

Fig. 2 is a similar view showing the egress end of the machine.

Fig. 3 is a top plan view of the machine.

Fig. 4 is a front elevation.

Fig. 5 is a rear elevation.

Fig. 6 is a detail transverse section through the gear casing.

Fig. 7 is a longitudinal sectional view in detail through the gear casing.

Fig. 8 is a detail, partly in section showing the adjustable bearings for the forming rolls.

Figs. 9 and 10 show the straightening rollers in front, and side elevation respectively.

Figs. 11 and 12 show a roller guide in plan and side elevation partly in section respectively.

Figs. 13 to 20 illustrate the steps in the process of the formation of the tubing by the machine.

The machine comprises a frame having side pieces 1 connected intermediately by webs 2 and tie bolts 3. The side pieces 1 on either side are provided with a cut-away shelf 4 at the front end thereof, providing a shoulder 5 for a purpose hereinafter to be described.

I scarf the abutting surfaces of the parts clamped together in this machine to provide an interrupted plane contact which makes possible a much closer fit and much more secure adjustment of the parts than if the reinforces were flat.

At the rear of the frame I provide a gear casing constructed as follows. The main portion of the gear casing is provided with two flanges 8 at right angles adapted to be secured upon the top and rear faces of the frame, as clearly shown in Fig. 6. Integrally formed with the flanges 8 is a worm trough 9, and a bearing supporting standard 10, reinforced at intervals by the webs 11, having bearings 12 and 13. Belted to the casing structure above the trough portion 9, and forming with the trough portion 9, a grease box for the gearing, to be described, is an angled cover plate 14. Bolted to the upper flange 8 by means of bolts 17 is a bearing standard 18 reinforced at intervals along its length by the webs 19 and having bearings 20 and 21. The bearing standards 18 and 10, the flanges 8 and the grease box formed by trough 9 and cover 14 run from one end of the machine to the other, and bearings 12, 13, 20 and 21 are provided to accommodate as many pairs of roll shafts as may be deemed to be necessary in the machine.

At one end of the machine the bearing standards 18 and 10 are enlarged at their tops to form a platform 22 upon which is mounted a driving motor 23 which may be of any known type. The drive pulley 24 of the motor drives a pulley 25 by means of a belt 26. The pulley 25 is mounted upon the shaft 27 which extends from one

end of the machine to the other. The end 65 bearings for the shaft 25 comprise bearing blocks 30 secured to the ends of the gear through 9 by means of bolts such as 31, (see Fig. 7). The bearing block 30 is provided with an annular threaded flange 32 over which is secured the grease cap 33, the space between the flange 32 and the shaft 27 being suitably packed with packing 34 held in sealing relation by the packing ring 35. The bearing at the opposite end of shaft 27 is substantially the same as that just described. Shaft 27 carries a plurality of worms 38 thereon, each keyed thereto and adapted to coöperate with worm gears 39 as hereinafter more fully described. The bottom of the trough 9 is provided with an upraised platform 40 between each pair of adjacent worms 38, upon which is mounted the bearing 41 detachably secured thereto by means of the bolts 42. On either side of the blocks 41 are disks 43 and 44 between which are mounted the ball bearing disks 45. This structure provides a ball bearing thrust bearing at a plurality of points along shaft 27 to accommodate any thrust arising in the resistance of the gearing 39 to rotation.

It will be observed that the trough 9 and cover plate 14 thus provide an oil tight grease box which may be filled with a lubricating medium and that the entire driving gearing of the machine may therefore run in oil.

The gears 39 driven by worms 38 are keyed to the shafts 45 which are mounted in bearings 12 and 20 respectively. Between the bearings 12 and 20 on the shafts 45 are gears 46 in mesh with gears 47 on shafts 48 journaled in the bearings 13 and 21.

I will now describe the mountings for the rollers. The cut away shelf 4 at the front end of the machine frame is provided with a plurality of key slots 6. These slots are adapted to receive corresponding keys 7 on the outer base member 51 of the standards adapted to carry the forming rolls. Each of these base members is of hollow reinforced, or web construction, (as shown in Fig. 8). The inner base member 50 is provided with a flange 52 adapted to overlie the shoulder 5 on the frame and to be secured thereto by suitable bolts. The inner base member 50 is rigidly fastened in place, but the outer member 51 is not immovably fastened directly on the shelf 4. The base members 50 and 51 are provided with aligned T-head slots 53, (as shown in Figs. 4 and 8). Seated upon the upper surfaces 54 of the members 50 and 51 are the intermediate sliding plates 55 each of which is of identical form and comprises an L-shaped angle plate having slots 56 in its lower horizontal web.

through which bolts 57, engaged with nuts 57' in T-slots 53 project to adjustably secure the sliding plates 55 with respect to the base members 50 and 51.

3 The base members 50 and 51 and the slide plates 55 each run the length of the machine. The slide plates 55 are provided with a plurality of heavy rectangular ribs 58 in each of which is cut a T-head slot 59. Seated 10 upon the upper surfaces of the ribs 58 just described, are the lower bearing plates 60, each of which is of identically the same form. These bearing blocks 60 each run the length of the machine and are of reinforced 15 or web construction having a lower web 61 (shown in dotted lines in Fig. 8 and full lines in Fig. 4) which has slots therein through which penetrate bolts 62 co-operating with nuts in T-slots 59 to firmly and adjustably hold the lower bearing portions 60 20 to the slide plates 55. Intermediate the recessed or webbed portion 61 of the plates 60 are bearing bosses 63. The ends of the lower bearing plates 60 are inturned and secured at each end by the bolts 64. By this construction it is apparent that the entire supporting structure comprising the inner and outer bearing standards is firmly fixed as regards relative horizontal displacement.

30 In the outer bearing standards are firmly fixed in relation to the inner standards, which in turn are secured to shoulder 5. The lower bearing plates 60 are each provided with a plurality of upstanding bosses 35 65 having threaded sockets which receive the lower threaded ends of a plurality of bolts 66 which extend through appropriate openings in the upper bearing blocks 67 and carry nuts 68 above the blocks 67. In the 40 sides of the upper bearing blocks 67 are lock bolts 70 which serve to firmly fix the bearing blocks 67 upon the bolts 66.

It will be seen from the drawings that the lower bearings 63 in lower bearing plates 60 45 are alined with the bearings 20 and 12. The lower shafts 45 are squared at their forward ends to receive the sockets 71 fixed upon square shaft 72, bolts 73 serving to keep these parts in position. At its opposite end 50 the shafts 72 carry sockets 74 fixed thereon, which fit over the squared ends of the shafts 75 journaled in bearings 63 in the lower bearing plates 60. Upon the shafts 75 and between the bearing plates 60 are mounted 55 the lower forming rolls. It will be understood that bearing plates 60 and bearing blocks 67 comprising the outer and inner bearings of the roller shafts may be separated along the axis of the roller shafts to 60 accommodate rolls of different thicknesses.

It is also desirable to permit the upper bearing blocks 67 to move vertically with respect to the lower bearing blocks to accommodate rolls of different diameters. To give

this adjustment, I provide the universal joint drive illustrated in Figs. 1 and 3. The upper shafts 48 in Fig. 6 which are geared to the lower shafts 45 are squared at their ends to receive sockets in the member 77 forming one-half of the universal joint construction 78, the other half of which at 79 are provided with square sockets to receive the square shafts 80. This structure is duplicated at the other end of the square shaft 80, the outer members 81 of the second universal joint construction having square sockets which receive the squared ends of the shafts 82 which are mounted in the alined bearings of the upper bearing blocks 67 and carry the upper forming rolls.

In the operation of the machine, the motor drives the worm shaft 27 which in turn drives all of the rolls at the same speed, the rolls of each pair being driven in opposite directions. Flat stock is fed to the machine 85 in the direction of the arrows shown in Fig. 3. If the rolls are of the form shown in Figs. 13 to 20 the first set of rolls I illustrated in Fig. 14 makes a partial bend in the stock as illustrated again in perspective 90 as indicated by numeral 14' in Fig. 13. The second set of rolls II makes a further bend in the stock as shown at 15' in Fig. 13. The third, fourth, fifth and sixth sets of rolls III to VI gradually form the stock into a tube 95 as sufficiently clearly illustrated in Figs. 13 to 20.

It is to be understood that many forms and varieties of forming rolls may be used in this machine, the specific embodiment of 100 the invention here illustrated disclosing six rollers, this number, however, being merely arbitrary and not material to the invention.

It is also to be understood that the tube can thereafter be provided with a groove to 105 receive plate glass or the stock may be bent into other forms than into a tube, all depending upon the number of rolls used and the shape thereof; variation in this respect being equally within the scope of the invention.

In front of the first pair of rolls I provide three rods 85, two upper and one lower preferably, which are mounted in suitable carriers 86 and serve to guide the flat stock 115 to the rolls in precisely horizontal plane.

Adjacent the rear end of the machine and suitably fastened to the projecting end of the base member 51, (see Figs. 9 and 10) I provide an upstanding bracket 87 having 120 an offset vertical plate 89 in which are three bearing slots 88. Overlapped upon the upper part of vertical plate 89 is an angled member 90 having angled portions 91 therein. A bolt 92 passes through the angle 125 portion 91 and is threaded into the upper end of the vertical plate 89. Threaded on bolt 92 are nuts 93 determining the vertical

position of the member 90. Through a bolt hole in plate 90 and the slot 88 in the member 89 projects the bolt 95. Sleeved upon this bolt is bushing 96. Bolt 95 is provided with an enlarged head at one end and a washer 97 and nut 98 at the other. A roller having a cut-away periphery 99 to accommodate in this instance a tube, is rotatably mounted upon this bushing. The construction of the two lower roll mountings is substantially the same, and will be readily understood from the drawings. By this construction the distance between the axes of the rolls may be varied, or the aperture therebetween may be raised or lowered, either or both. The lower rolls 102 are similar to the upper roll 99. The purpose of this mechanism is to straighten out the tubing as it comes out of the machine and to counteract any tendency to bend or curl.

To prevent the stock from becoming distorted with relation to the rolls in its progress through the machine, I provide one or more straightening devices, only one of which is here illustrated (see Figs. 3, 11 and 12), inasmuch as all thereof are precisely the same. The device comprises plate 105, having slots 105', carrying an upstanding bearing bracket 106 between which and the plate 105 is journaled the horizontal roller 107. The rear end of the plate 105 is downturned and is adjusted on the machine as regards movement back and forth at right angles to the path of the stock by a suitable bolt 108. The plate 105 is secured by the bolts 109 to the machine, passing through the slots 105.

I claim:

1. In a metal forming machine, a frame, a rear base member extending longitudinally of the frame and movable at right angles to the length thereof by means of slideable connections therewith, a front base member spaced from the rear base member and similarly mounted upon the frame, an intermediate plate adjustably mounted upon each of the base members, a lower bearing plate adjustably mounted upon each of the intermediate plates, said lower base plates being rigidly adjustably connected at their extremities, bearings in said lower bearing plates, rollers in said bearings.

2. In a metal forming machine, a frame, a rear base member extending longitudinally of the frame and movable at right angles to the length thereof by means of slideable connections therewith, a front base member spaced from the rear base member and similarly mounted upon the frame, an intermediate plate adjustably mounted upon each of the base members, a lower bearing plate adjustably mounted upon each of the intermediate plates, said lower base plates being rigidly adjustably connected, upper bearing blocks mounted for vertical adjustment upon the lower plates, rollers journaled in said bearing blocks whereby the upper and lower bearings of the rollers may be moved apart or together and whereby the axes of the upper and lower rollers may be adjusted relatively toward and from each other.

3. In a machine of the character described, comprising a support, base members mounted thereupon, slide plates adjustably mounted upon said base members, bearing plates adjustably supported upon the slide plates, means for rigidly connecting the extremities of the bearing plates, bearing blocks vertically adjustable upon the bearing plates, and metal forming rolls journaled within said bearing plates and blocks.

4. In a metal forming machine comprising a support, a pair of base members carried by the support, slide plates extending parallel with and arranged upon the base members, a pair of bearing plates laterally adjustable upon the slide plates, means for rigidly connecting the ends of the bearing plates, a plurality of vertical pins detachably secured to the bearing plates, bearing blocks adjustably mounted upon said pins, means for locking the bearing blocks upon the pins, and metal forming rolls journaled within the bearing blocks and plates for the purpose specified.

In witness whereof, I hereunto subscribe my name to this specification in the presence of two witnesses.

JOHN A. FRASER.
